(57) **CLAIM**

The ornamental design for a window seal extruded weather-strip, as shown and described.

DESCRIPTION

FIG. 1 is a perspective view of the window seal extruded weatherstrip showing our new design;
FIG. 2 is a front elevation view thereof;
FIG. 3 is a top plan view thereof;
FIG. 4 is a side elevational view thereof;
FIG. 5 is a bottom plan view thereof;
FIG. 6 is a second side elevational view thereof; and,
FIG. 7 is a rear elevation view thereof.

The window seal extruded weatherstrip is shown broken in the center to indicate that indeterminate length.
